DISPOSABLE DRINKING CUP

Jack K. McFarland and Wilmer C. Neiss,
Billings, Mont.

Application July 3, 1950, Serial No. 171,804

1 Claim. (Cl. 229—52)

1

This invention relates to a disposable drinking cup and it is one object of the invention to provide a cup which is formed of paper, cardboard, or the like, the bottom and the walls of the cup being covered with thin metal foil which serves to water proof the material from which the cup is formed and also prevent the flavor of liquid poured into the cup from being impaired.

Another object of the invention is to provide a paper cup which has a body or annular wall formed from a paper blank having one surface covered with metal foil except one end portion, thereby allowing the bare end portion of the paper sheet to be adhesively secured in overlapping engagement with the other end portion of the sheet and firmly hold the ends of the blank together and form an annular wall for the cup.

Another object of the invention is to provide the cup with a handle so mounted that it may be disposed in a flattened position when the cup is made and drawn outwardly to an extended position when the cup is to be filled and held in a person's hand.

Another object of the invention is to provide a disposable paper cup which is simple in construction and may be manufactured at low cost.

The invention is illustrated in the accompanying drawings wherein:

Fig. 1 is a view of the blank from which the paper portion or annular wall of the cup is formed.

Fig. 2 is a sectional view taken vertically through the cup.

Fig. 3 is a sectional view taken transversely through the cup.

This improved cup has a body or annular wall 1 and a bottom 2. The body tapers towards its lower end so that the bottom fits tightly in the lower portion of the body, and upon referring to Figure 2 it will be seen that the bottom has its marginal portion bent downwardly to form a depending flange 3. This flange has close fitting contacting engagement with the annular wall or body and the lower end portion of the body is bent inwardly and upwardly to form a flange or circumferentially extending lip 4 which overlaps the flange 3 and bears against the under surface of the bottom 2 and supports the bottom as well as forming a water tight point between the bottom and the annular wall 1.

The annular wall or body is formed from the blank 5 shown in Figure 1. This blank may be formed of paper, cardboard, or other suitable material, and is arcuate longitudinally and its end edges are cut diagonally so that they extend

downwardly in converging relation to each other. Therefore when one end portion of the blank is secured in overlapping engagement to the other end portion of the blank the body or annular wall 5 formed thereby will taper towards its lower end. The surface of the blank or sheet 5 which is presented upwardly in Figure 1 and forms the inner surface of the body 1 has applied to it a covering 6 formed of metal foil which is preferably glued to the paper sheet. This covering or lining extends the full distance between upper and lower edges of the blank and has one end overlapping the edge of the corresponding end of the sheet, as shown at 6' in Figure 3, and its other end 10 disposed in inwardly spaced relation to the corresponding end of the sheet. Therefore one end portion 5' of the paper sheet is bare and this end portion may be very tightly glued in face to face engagement with the end portion of the outer surface of the paper sheet which it overlaps. This is clearly shown in Figure 3, and referring to this figure it will be seen that the portion 6' of the metal foil forms a water tight seal and very effectively prevents hot or cold liquid poured 15 into the cup from flowing or seeping through a crevice between the overlapped end portions of the sheet forming the body or annular wall. The paper disk forming the bottom has its upper surface covered with a sheet of metal foil 7 and as its marginal portions which are turned downwardly with the portion of the bottom forming the flange 3 has face to face contacting engagement with the metal foil lining for the annular wall or body 1 a water tight seal is formed 20 between the bottom and the wall. The upper edge portion of the wall or body is rolled outwardly and downwardly to form a bead or rolled lip 8 providing a smooth marginal edge for the cup.

30 In order that the cup may be held while it is being used there has been provided a handle 9 which is formed from a strip of paper of an even width throughout its length except at its ends which are enlarged to form heads 10. The heads are triangular with their wide ends disposed 35 at their junction with the main portion of the handle-forming strip, thus forming shoulders 11 at opposite sides of the inner ends of the heads. A slit 12 is formed in the bare end portion 5' of the blank from which the body is formed. This slit is substantially U-shaped and has arms 13 at its upper and lower ends which extend transversely of the bare end portion of the blank and together with the longitudinally extending 40 portion of the slit form a tongue 14 under which

the handle-forming strip is fitted. The handle extends vertically with its end portions projecting from upper and lower ends of the tongue 14 and is initially disposed in the flattened condition shown in Figure 1. When the cup is to be used the portion of the handle-forming strip exposed outwardly of the cup is grasped and pull exerted until the heads stop its outward movement, thus forming a semi-circular handle, as shown in Figure 2, the handle being of such size that it may be readily grasped and the cup held in a person's hand.

Having thus described the invention, what is claimed is:

A disposable drinking cup comprising an annular wall consisting of a sheet of paper having one end portion overlapping the outer surface of the other end portion of the sheet, the overlapping end portion of the sheet being adhesively secured flat against the confronting surface of the overlapped end portion of the sheet, a bottom for the cup having marginal portions secured to lower portions of the annular wall, the overlapping end portion of said sheet being formed with a vertically extending slit and transverse slits extending from upper and lower ends of the vertical slit and together therewith forming a tongue free along one side edge and across upper and lower ends and along its other side being integral with the said overlapping end portion of the said sheet, and an initially flat strip extending vertically along the outer surface of the overlapping

end portion of wall-forming sheets and transversely overlapped for its full width by said tongue and having end portions extending beyond upper and lower ends of said tongue into space between 5 the said end portions of the sheet and terminating in widened ends constituting heads having base portions projecting from opposite side edges of the strip under the said overlapping end 10 of said sheet for engaging upper and lower ends of said tongue and holding the strip in engagement with the wall, said strip being slidable longitudinally through the laterally extending end portions of the slit whereby the intermediate portion of the strip may be drawn outwardly and 15 form an outstanding U-shaped handle anchored at its ends by the heads of the strip.
